(57) **CLAIM**

The ornamental design for a typeface, as shown and described.

DESCRIPTION

1.-11. Typefaces

FIG. 1.1 illustrates a first embodiment of the typeface, including primary and alternate characters and symbols, in a light italic format;

FIG. 1.2 is a face view showing the letters of FIG. 1.1 in use;

FIG. 2.1 illustrates a second embodiment of the typeface, including primary and alternate characters and symbols, in light format;

FIG. 2.2 is a face view showing the letters of FIG. 2.1 in use; FIG. 3.1 illustrates a third embodiment of the typeface, including primary and alternate characters and symbols, in a condensed light format;

FIG. 3.2 is a face view showing the letters of FIG. 3.1 in use; FIG. 4.1 illustrates a fourth embodiment of the typeface, including primary and alternate characters and symbols, in a regular format;

FIG. 4.2 is a face view showing the letters of FIG. 4.1 in use; FIG. 5.1 illustrates a fifth embodiment of the typeface, including primary and alternate characters and symbols, in italic format;

FIG. 5.2 is a face view showing the letters of FIG. 5.1 in use; FIG. 6.1 illustrates a sixth embodiment of the typeface, including primary and alternate characters and symbols, in a condensed format;

FIG. 6.2 is a face view showing the letters of FIG. 6.1 in use; FIG. 7.1 illustrates a seventh embodiment of the typeface, including primary and alternate characters and symbols, in a semi-bold format;

FIG. 7.2 is a face view showing the letters of FIG. 7.1 in use; FIG. 8.1 illustrates an eighth embodiment of the typeface, including primary and alternate characters and symbols, in a semi-bold italic format;

FIG. 8.2 is a face view showing the letters of FIG. 8.1 in use; FIG. 9.1 illustrates a ninth embodiment of the typeface, including primary and alternate characters and symbols, in a condensed bold format;

FIG. 9.2 is a face view showing the letters of FIG. 9.1 in use; FIG. 10.1 illustrates a tenth embodiment of the typeface, including primary and alternate characters and symbols, in a bold format;

FIG. 10.2 is a face view showing the letters of FIG. 10.1 in use;

FIG. 11.1 illustrates an eleventh embodiment of the typeface, including primary and alternate characters and symbols, in a condensed bold italic format; and

FIG. 11.2 is a face view showing the letters of FIG. 11.1 in use.

The exemplary alphabet sentences shown in FIGS. 1.2; 2.2; 3.2; 4.2; 5.2; 6.2; 7.2; 8.2; 9.2; 10.2; and 11.2 illustrate the claimed typeface of font in use. The words shown form no part of the claimed design.
